United States Patent Office

Des. 174,430
Patented Apr. 12, 1955

174,430

CROSS ARM FOR A PLAYGROUND APPARATUS OR SIMILAR ARTICLE

Isadore Horowitz, Shreveport, La.

Application April 28, 1954, Serial No. 30,232

Term of patent 14 years

(Cl. D34—5)

Fig. 1.

Fig. 2.

To all whom it may concern:

Be it known that I, Isadore Horowitz, a citizen of the United States, residing at Shreveport, in the parish of Caddo and State of Louisiana, have invented a new, original, and ornamental Design for a Cross Arm for a Playground Apparatus or Similar Article, of which the following is a specification, reference being had to the accompanying drawing, forming part thereof.

Figure 1 is a top perspective of a cross arm for a playground apparatus or similar article, showing my new design, and

Figure 2 is a bottom perspective view thereof.

I claim:

The ornamental design for a cross arm for a playground apparatus or similar article, as shown.
